UNITED STATES PATENT OFFICE.

LUCIAN C. JACKSON, OF BUFFALO, NEW YORK.

GAS-ENGINE.

1,172,362.

Specification of Letters Patent. Patented Feb. 22, 1916.

Application filed May 31, 1907. Serial No. 376,671.

To all whom it may concern:

Be it known that I, LUCIAN C. JACKSON, a citizen of the United States, residing at Buffalo, in the county of Erie and State of New York, have invented or discovered a certain new and useful Improvement in Gas-Engines, of which improvement the following is a specification.

The object of my invention is to provide an improvement in internal combustion engines; and it consists in a new and improved internal combustion engine which is compact and simple in construction, with all parts readily accessible, quiet and economical in operation, and adapted to maintain a regular and uniform rotation of the main shaft, in a new and improved valve gear and method of operating the engine when running and in the novel features of construction and combination of parts hereinafter set forth.

In the accompanying drawings which illustrate an application of my invention, Figure 1 is a side elevation of a two cylinder gas engine embodying my invention, and showing the method of operating the valves from the cam shaft and the method of driving the cam shaft from the main shaft through the medium of an intermediate or side shaft and spiral gears; Fig. 2, an end elevation showing the cylinder heads, governor and throttling valve, cam shaft, and valve gear; Fig. 3, a top view showing the electric igniter and starting valve and connections to the left hand cylinder; Fig. 4, a section through the engine on the line A—B of Fig. 2, showing the fly-wheel, governor and throttling valve; Fig. 5, a detail, partly in section, of the inlet valve lever used on the left hand cylinder; Fig. 6, a detail, partly in section, of the inlet valve lever used on the right hand cylinder; Fig. 7, a detail, partly in section, of the exhaust valve lever used on the right hand cylinder and which is the same on both cylinders; Figs. 8 and 9, central longitudinal sections of the equalizing mechanism used on the cam shaft; Fig. 10, a perspective view and Fig. 11 an end view of the cam shaft showing the arrangement of the cams for operating the inlet and exhaust valves.

In the drawings, 1 represents the bed of a two cylinder horizontal gas engine arranged to accommodate the flywheel 2 between the cylinders 3 and 4. The valve chests 5 and 6 are formed in one piece with the cylinder

heads 7 and 8. 9 is the crank shaft on one end of which is mounted a spiral gear 10 which meshes with spiral gear 11 on one end of the side shaft 12. Spiral gear 13 is mounted on the opposite end of side shaft 12 and meshes with spiral gear 14 on one end of the cam shaft 15. Cam shaft 15 is placed at the end of the engine bed parallel to the crankshaft 9 and underneath the cylinders 3 and 4, and on which the cams 16, 17, 18 and 19 are mounted to operate the valves 20, 21, 22 and 23 through the medium of the levers 24, 25, 26 and 27. The valves 20 and 23 are the exhaust valves and 21 and 22 are the inlet valves for the cylinders 3 and 4 respectively. 28, 28 and 29, 29 are exhaust and inlet valve springs to hold the valves closed except when opened by means of the cams 16, 19 and 17, 18. On the cam shaft 15 are also mounted eccentrics 30, 30 for operating the electric igniters 31, 31. The governor 32, operated by means of bevel gears 33 and 34, controls the throttling valve 35.

Cam 36 on the shaft 15 (Fig. 2) operates the equalizing gear shown in detail in Figs. 8 and 9.

In my plan of construction, arrangement of valve gear and method of operating the same I have novel and improved features of construction. The valve gear being driven as shown allows of placing the flywheel between the two cylinders and next to two supporting bearings which is the nearest point to each of the cylinders. The energy from each cylinder in turn is thus transferred to the flywheel and delivered to either side of the engine with less strain on the crankshaft than by placing the flywheel at one side and an extra outboard or an overhung flywheel on each side, which in either of the latter cases causes a continual reversal of strains through the entire length of the crankshaft.

In Fig. 2, I show the crankshaft extending beyond the outside bearing on the left hand cylinder and broken off, indicating that the power is to be taken off at that side, but it can be taken off at either or both sides or by means of a belt from the rim of the flywheel.

My method of driving the valve gear by means of two sets of spiral gears makes the operation of the engine practically noiseless and at the same time allows me to use horizontal side and cam shafts which operate

in different planes. This construction is of advantage as any convenient size of gears can be used and still the cam shaft can be placed in the most advantageous position to 5 operate the valves vertically in the cylinder head. As shown, the side shaft is driven at the same speed as the crankshaft and the cam shaft at one half that speed. If desired the side or intermediate shaft could be 10 driven faster or slower than the crank shaft and the cam shaft still be driven at one half the speed of the crank shaft and the same size gears be used by changing the angle and hence the number of the spiral gear 15 teeth, which would not be possible when using bevel or spur gears.

In the different figures, arrows indicate the direction of rotation of the flywheel and crank shaft, side and cam shafts. 20 The engine, as shown, is of the well-known four-cycle type, in which suction, compression, impulse and exhaust follow each other in each cylinder during four strokes of the piston to make the complete 25 cycle. The cam shaft which operates the valves is consequently rotated at one half the engine speed, and the cams which open the valves timed to open the inlet valve during the suction stroke and to open the 30 exhaust valve during the exhaust stroke. During the compression and impulse strokes the valves are closed.

Two forms of inlet valve levers are shown 35 in Figs. 5 and 6. The construction shown in Fig. 5 can be used on a cylinder so that it may be thrown out of action at any time and the engine run on the other cylinder. In this way one cylinder may be thrown 40 out of action for any purpose such as replacing a spark plug and without shutting down the engine. In the present instance the cylinder 4 has an inlet valve lever as shown in Fig. 5 and cylinder 3 has an inlet 45 valve lever as shown in Fig. 6.

In Fig. 5, 38 is a handle fastened to the lever 26 by means of a screw 39 on which it is pivoted. 40 is an adjustable stud screwed into the handle 38 and locked in place by means of a set screw 41. 42 is a lock bolt 50 projecting up into a recess 47 in the handle 38 which it locks in place. 43 is a recess in the upper end of lock bolt 42. 44 is a spring in the end of lever 26 which holds the lock bolt 42 in its position to keep 55 the handle 38 in place. 45 is a knurled nut on the lower end of lock bolt 42 and fastened solidly to it by means of the nut 46 and shoulder 48. 49 is a small round projection on the knurled nut 45 which fits in a suitable hole in the lever 26.

To render valve 22 inoperative the lock bolt 42 is first pulled down by means of the knurled nut 45 until the projection 49 clears the bottom surface 50 of the lever 26 when 60 the upper end of 42 is out of the recess 47,

and then a partial rotation of the knurled nut 45 holds the lock bolt 42 down as 49 rests against the surface 50. The handle 38 is now swung around on the pivot 39 so the stud 40 does not touch the valve 22 when 70 the lever 26 is operated by the cam 18. While the engine is running the cam 18 operates the lever 26 in its regular manner at every revolution of the cam shaft 15, but the valve 22 remains closed until the 75 handle 38 is swung back and locked into the position shown in Fig. 5 when the cylinder 3 is in regular operation.

The inlet lever 25 for operating the inlet valve 21 for cylinder 3 (Fig. 6) has a stud 54, which is screwed into it and locked in place by means of the nuts 55 and 56. The stud 54 is adjustable up and down in the lever 25 by means of screw threads. The roller ends and rollers 52, 52, etc., are the 80 same on the levers 24, 25, 26 and 27. The inlet cams 17 and 18 are alike and the exhaust cams 16 and 19 are alike.

In Fig. 7 is shown a detail of the exhaust lever 24 and cam 16 which is the same as the 90 exhaust lever 27 and cam 19. 57 is a stud screwed into lever 24 and having a nut 58 locked in place by means of the set screw 59. 64 is a squared part on the stud 57 on which the handle 63 is held by the nut 65. 62 is a pin in the lever 24 backed by the spring 61 and plug 60 and which fits into a depression in the handle 63 for holding it in the position shown. The exhaust relief cam 53 is a slight raise on the back 100 of the cam 16 and which just touches the roller 52 when the stud 57 is in contact with the valve 20 and without raising the valve 20 from its seat. The raise or cam 53 is next to the roller 52 during part of the compression stroke and to relieve the compression during this part of the stroke, the handle 63 is swung around when the stud 57 is raised by means of its threaded portion 105 in the lever 24 and until the handle 63 strikes the lower surface 66 of the lever 24. The raise 53 will then lift the valve 20 from its seat and allow part of the compressed charge to escape into the exhaust pipe at each revolution of the cam shaft 15 until 115 the handle 63 is again swung back to its position shown in Fig. 7 and the nut 58 again resting on the top of the lever 24.

99 (Figs. 8 and 9) is a casing having a flange 100 by which it is fastened to the engine. 101 is a spring in the casing 99 between the adjustable plug 102 at the top and the slide 103 at the bottom which has a roller 104 for running on the cam 36. The cam 36 is made of such a shape as to cause the spring 101 to exert a pressure directly opposite and as near equal at all times to the pressure exerted by the valve springs on the cams 16, 17, 18 or 19 as desired. Figs. 9 and 11 show the cams 36 and 16, 17, 18 and 120 125 130

19 in their relative positions. As the roller 52 starts to rise on cam 18 the roller 104 starts to fall on 105 of cam 36 and as roller 52 falls on the opposite side of cam 18 roller 104 rises on 106 of cam 36. As shown in 5 Figs. 10 and 11 the four cams 16, 17, 18 and 19 are spaced around the cam shaft 15 to open and close first one valve and then another for the proper operation of the 10 engine and consequently spring 101 equalizes each of the valve springs in turn.

The valve springs 28, 28 and 29, 29 exert considerable pressure on the cam shaft when the valves 21, 22, 23 and 24 are opened and closed, and this pressure is reversed during the rise and fall of each valve. When not equalized, this continual reversal of pressure on the cam shaft throws it forward and back an amount equal to the clearance in the 20 teeth of the gears 13 and 14 and also acts in the same manner on the side shaft 12. This vibration of the cam shaft is not noticeable except by the jumping of the governor which is objectionable as impairing its 25 sensitiveness and reliability. By the use of the equalizing mechanism described the pressure on the cam shaft 15 and side shaft 12 and consequently on the gears 13, 14, 10 and 11 can be reduced to a very small amount and 30 made to act always in one direction so a governor operated either from the camshaft or side shaft would not be subjected to vibration.

I claim as my invention and desire to set 35 cure by Letters Patent—

1. In a gas engine having a combustion chamber, an inlet valve to control the inlet opening to said chamber and a valve gear to operate said valve, said valve gear including a lever for operating the inlet valve, said lever having a contact member for opening the inlet valve and being adapted to be moved into and out of operative position with said valve.

2. In a gas engine having a combustion chamber, an exhaust valve to control the exhaust opening to said chamber and a valve gear to operate said valve, said valve gear including a lever for operating the exhaust valve, said lever having a contact member for opening the exhaust valve and being adapted to be adjusted whereby the exhaust valve will be partially opened on the compression stroke of the engine.

3. In a gas engine having a combustion chamber, inlet and exhaust valves to control the inlet and exhaust openings to said chamber and a valve gear to operate said valves, a contact member to open the inlet valve and 55 adapted to be moved into and out of operative position with said valve, and a contact member to open the exhaust valve and adapted to be adjusted whereby the exhaust

valve will be partially opened during the compression stroke of the engine.

4. In a gas engine having an inlet valve, valve gear to operate said valve, the valve operative end of said gear having a contact member locked in operative position and adapted to be unlocked and moved out of 65 operative position with said valve.

5. In a gas engine having an inlet valve, a spring to hold said valve closed, valve gear to operate said valve against the action of 75 said spring, the valve operative end of said gear having an adjustable contact member locked in operative position and adapted to be unlocked and moved out of operative position with said valve.

6. In a gas engine having an inlet valve, 80 a spring to hold said valve closed, valve gear to operate said valve against the action of said spring, said valve gear having an adjustable contact member locked in operative position to open said valve and adapted to 85 be unlocked and adjusted to vary the amount of opening of said valve.

7. In a gas engine having a combustion chamber, a valve, valve gear to operate said valve, said valve gear having an adjustable 90 contact member locked in position to operate said valve and adapted to be unlocked and moved out of operative position with said valve, and a cam shaft driven by means of spiral gears.

8. In a gas engine, a cylinder having a combustion chamber, a valve adapted to control an inlet port into said chamber, a valve mechanism to operate said valve, said mechanism consisting of an intermediate shaft 100 and a cam shaft driven by means of spiral gears, a lever for operating said valve by means of a cam on said cam shaft, a pivoted handle on the valve operating end of said lever with an adjustable valve contact stud 105 and a spring actuated lock for holding said pivoted handle in operative position.

9. In a gas engine, a cylinder having a combustion chamber, a valve adapted to control an exhaust port in said chamber, a 110 valve mechanism to operate said valve, said mechanism consisting of an intermediate shaft and a cam shaft driven by means of spiral gears, a lever for operating said valve by means of a cam on said cam shaft, an adjustable contact stud in the valve operating end of said lever with a handle and a spring actuated locking pin for holding said contact stud in normal operative position.

In testimony whereof I hereunto affix my 120 signature in the presence of two witnesses.

LUCIAN C. JACKSON.
